(57) **CLAIM**

The ornamental design for a feminine hygiene pad, as shown and described.

DESCRIPTION

FIG. 1 is a perspective view of an embodiment of a sanitary napkin embodying our new design;

FIG. 2 is a front elevational view of the embodiment of FIG. 1, the rear elevational view being a mirror image thereof;

FIG. 3 is a top plan view of the embodiment of FIG. 1;

FIG. 4 is a bottom plan view of the embodiment of FIG. 1;

FIG. 5 is a right side elevational view of the embodiment of FIG. 1, the left side being a mirror image thereof;

FIG. 6 is a perspective view of another embodiment of a sanitary napkin embodying our new design;

FIG. 7 is a front elevational view of the embodiment of FIG. 6, the rear elevational view being a mirror image thereof;

FIG. 8 is a top plan view of the embodiment of FIG. 6;

FIG. 9 is a bottom plan view of the embodiment of FIG. 6;

FIG. 10 is a right side elevational view of the embodiment of FIG. 6, the left side being a mirror image thereof.

FIG. 11 is a perspective view of another embodiment of a sanitary napkin embodying our new design;

FIG. 12 is a front elevational view of the embodiment of FIG. 11, the rear elevational view being a mirror image thereof;

FIG. 13 is a top plan view of the embodiment of FIG. 11;

FIG. 14 is a bottom plan view of the embodiment of FIG. 11;

FIG. 15 is a right side elevational view of the embodiment of FIG. 11, the left side being a mirror image thereof;

FIG. 16 is a perspective view of yet another embodiment of a sanitary napkin embodying our new design;

FIG. 17 is a front elevational view of the embodiment of FIG. 16, the rear elevational view being a mirror image thereof;

FIG. 18 is a top plan view of the embodiment of FIG. 16;

FIG. 19 is a bottom plan view of the embodiment of FIG. 16;

FIG. 20 is a right side elevational view of the embodiment of FIG. 16, the left side being a mirror image thereof;

FIG. 21 is a perspective view of a further embodiment of a sanitary napkin embodying our new design;

FIG. 22 is a front elevational view of the embodiment of FIG. 21, the rear elevational view being a mirror image thereof;

FIG. 23 is a top plan view of the embodiment of FIG. 21;

FIG. 24 is a bottom plan view of the embodiment of FIG. 21; and,

FIG. 25 is a right side elevational view of the embodiment of FIG. 21, the left side being a mirror image thereof.

The broken line showing of each embodiment of the feminine hygiene pad in FIGS. 1 through 25 is illustrative of the environmental structure only, and forms no part of the claimed design.
